DESIGN FOR A BOMB SHIELD

Martin J. Leuer, San Francisco, Calif.

Application February 25, 1942, Serial No. 105,979

Term of patent 3½ years

To all whom it may concern:

Be it known that I, Martin J. Leuer, a citizen of the United States, residing at the city and county of San Francisco and State of California, have invented a new, original, and ornamental Design for a Bomb Shield, of which the following is a specification, reference being had to the accompanying drawing, forming part thereof.

Fig. 1 is a rear perspective view of a bomb shield, showing my new design.

Fig. 2 is a top plan view of the bomb shield.
Fig. 3 is a front elevational view of the bomb shield, and

Fig. 4 is a side elevation view, thereof.

I claim:

The ornamental design for a bomb shield, substantially as shown.

MARTIN J. LEUER.
